United States Patent Office

Des. 220,475
Patented Apr. 20, 1971

220,475

BUILDING

Elliott H. Brenner, Lafayette, Ind., assignor to
Araneida, Inc., West Lafayette, Ind.

Filed June 22, 1970, Ser. No. 23,602

Term of patent 14 years

Int. Cl. D25—04

U.S. Cl. D13—1

FIG. 1.

FIG. 4.

FIG. 2.

FIG. 3.

FIG. 5.

FIG. 6.

FIG. 9.

FIG. 7.

FIG. 10.

FIG. 8.

FIG. 1 is a perspective view of a building embodying the design of the present invention;

FIG. 2 is a front elevational view of the building of FIG. 1;

FIG. 3 is a side elevational view of the building of FIG. 1, both sides being identical;

FIG. 4 is a plan view of the building of FIG. 1;

FIG. 5 is a rear elevational view of the building of FIG. 1;

FIG. 6 is a perspective view of a building constituting a second embodiment of the invention;

FIG. 7 is a front elevational view of the building of FIG. 6;

FIG. 8 is a side elevational view of the building of FIG. 6, both sides being identical;

FIG. 9 is a top plan view of the building of FIG. 6; and

FIG. 10 is a rear elevational view of the building of FIG. 6.

I claim:

The ornamental design for a building, as shown and described.
